DRY KILN

R. A. Simmons, Vernonia, Oreg.

Application September 1, 1951, Serial No. 244,817

4 Claims. (Cl. 34—191)

1

This invention relates in general to dry kilns, and, in particular, to kilns for drying lumber, especially dry kilns for lumber in which the drying currents of air pass in a more or less horizontal direction through the stacked lumber and in which the passage of air is reversed from time to time so that the drying will take place uniformly.

One of the objects of the invention is to provide an improved dry kiln in which the flow of the drying currents of air and the reversal of the direction of the same will be controlled in a very easy and in a very simple manner.

Another object of the invention is to provide an improved dry kiln in which the delivery of air into, and the withdrawal of air from the kiln, regardless of the direction of passage of air through the lumber, will occur at the top of the kiln, thus enabling the floor of the kiln to be at ground level as a convenience in moving cars of lumber into and out of the kiln.

A related object of the invention is to provide an improved lumber kiln in which control of the humidity and temperature of air in the kiln, as well as control of air movement, will all be regulated from the top of the kiln.

An additional object of the invention is to provide a dry kiln of simple and practical construction having a forced air circulation controlled in a simple and practical manner, and in which the air currents and the air circulation will always be uniform throughout the entire length of the kiln.

The manner in which these objects are attained, together with incidental advantages, and the manner in which my improved kiln is constructed and arranged, will be briefly described with reference to the accompanying drawings, in which:

Fig. 1 is a more or less diagrammatic longitudinal, sectional, elevation of the kiln taken on line 1—1 of Fig. 3;

Fig. 2 is a similar longitudinal sectional elevation of the kiln taken on line 2—2 of Fig. 3;

Fig. 3 is a plan section taken on lines 3—3 of Figs. 1 and 2;

Fig. 4 is a fragmentary enlarged sectional elevation corresponding in part to Fig. 1; and

Fig. 5 is a considerably enlarged vertical transverse section on line 5—5 of Fig. 3.

The kiln includes a pair of side walls 10 and 11, having no openings, a pair of end walls 12 and 13, at least one of which has a door (not shown) to permit carloads of lumber L, (such a carload being indicated in broken lines in Fig. 5),

to be moved into and out of the kiln, and a ceiling wall 14.

Along each side of the ceiling 14 is a row of slot openings 15 of identical size and equally spaced apart. Each slot opening extends a short distance inwardly and transversely from the side edge of the ceiling. The purpose of these slot openings 15 is to enable the drying air to be passed into the kiln through the slot openings 15 along one side and then to be withdrawn from the kiln through the slot openings along the other side, as will presently appear.

Two pairs of air ducts 16, 17 and 18, 19 are positioned above the ceiling wall 14 of the kiln as shown in Fig. 3, so as to extend entirely over the slot openings 15, the air ducts of each pair thus extending along on opposite sides of the ceiling wall 14. Preferably these four air ducts are identical in size and shape. The air ducts along each side come together at the approximate longitudinal middle point along the kiln. Each of these ducts constitutes a housing with side walls and a sloping roof. The roofs of the ducts have a constant downward slope from the end of the duct adjacent an end of the kiln to the opposite end of the duct or the longitudinal middle point of the kiln, as shown in Fig. 1.

A pair of air chambers 20 and 21, located above the ceiling wall respectively at opposite ends of the kiln, connect the pairs of air ducts at the ends of the kiln. Each chamber has a pair of ports 22 connecting the chamber with the adjacent ducts respectively, and an air circulating fan 23 is located in each port. Preferably the ports 22 are circular, having a diameter only slightly greater than the diameter of the fans 23 located within the ports, and also preferably the area of each port 22, and the corresponding area of each fan 23, approximately equals the total area of the slot openings 15 covered by each duct. The fans 23 are driven by electric motors 24 through the medium of suitable reduction drives, the fan motors being located in a motor room 25, behind each air chamber, and the fan shafts extend through the air chambers and are supported in suitable bearings (not shown). Reversible controls (not shown) for the fan motors 24 are provided in the motor room 25 and the fan motors are so arranged that the two fans of each air chamber will be driven in opposite directions. Thus, as indicated by the arrows in Fig. 5, the fans during one period of operation are operated to draw the air from the ducts 16 and 18 into the chambers 20 and 21 respectively and to drive the air thence into the ducts 17 and 19 respec-

tively. Similarly, when the operation of the fans is reversed, air is drawn from the ducts 17 and 19 and forcibly delivered into the ducts 16 and 18.

An air inlet 26 (Figs. 1, 2 and 4) is located on top of each of the ducts 16, 17, 18 and 19. The purpose of these inlets is to permit fresh air from the outside to be drawn into the ducts and thence into the kiln. The air inlets 26 have hinged covers or lids with upstanding arms which are connected by linkage to lever arms operated by diaphragm-controlled motors, one of which is indicated at 27 in Fig. 1. Whenever the air pressure within the duct is less than the atmospheric pressure outside of the kiln, these motors 27 will operate to cause the air inlets 26 for the two ducts on the suction side of the kiln, that is to say, the two ducts from which air is being drawn from the kiln into the respective air chambers, to open. This allows some fresh air to be mixed with the air withdrawn from the kiln before such air is returned into the kiln. Meanwhile the inlets 26 on the opposite ducts, that is to say, the ducts into which the air from the chambers is driven and from which the air then moves down into the kiln, are kept closed. While only one inlet 26 is shown on the roof of each duct in the drawings, it may be desirable to have a plurality of such inlets on each duct in the case of a very large kiln. In such event the inlets 26 on each duct are connected together so as to be operated in unison in the same manner.

A plurality of ventilators 28 (Figs. 2 and 5) are located along the center line of the ceiling between the ducts of each pair and are spaced apart equal distances throughout the length of the kiln. Each ventilator 28, like the air inlets 26, has a lid or cover with an upstanding arm. The arms of the covers of the ventilators are connected by suitable linkage so that all the ventilators 28 will be opened and closed simultaneously. The purpose of these central roof ventilators 28 is to allow air to be exhausted or discharged from the kiln whenever the kiln air becomes too hot or too humid, and these ventilators, due to their central position, will discharge the air from the top central portion of the kiln. The opening and closing of these ventilators 28 is done by suitable motor, indicated at 29 in Fig. 2, which in turn is controlled by an automatic temperature and humidity control regulator of a type which is well known and extensively used and which therefore need not be described.

Baffles 30 and 31 (Figs. 2 and 5), extending longitudinally of the kiln and parallel to the side walls, are suspended from the ceiling wall in the relative positions illustrated in Fig. 5, thus being positioned inside the inner ends of the slot openings 15. These baffles extend down a short distance from the ceiling and their purpose is to prevent any short-circuiting of the air currents at the top of the kiln. Thus the incoming air currents passing down through the slot openings 15 at one side of the kiln will be required to pass down into the kiln first before moving laterally across the kiln to the other side and thence moving up and out of the kiln through the slot openings in the ceiling on the other side of the kiln. Preferably also corresponding lower baffles 32 and 33 (Fig. 5) extend a short distance upwardly from the floor of the kiln in substantial vertical alignment with the ceiling baffles 30 and 31. These lower baffles prevent cross currents of air occurring along the kiln floor and under the cars which carry the lumber. The lumber is

carried on cars in the usual manner and these cars move on rails 34 provided on the floor of the kiln. The lumber is stacked on the cars in horizontal layers as is customary. Consequently the drying currents of air in the kiln pass crossways through the lumber stacks and between the layers of lumber.

Steam heating pipes 35 and a main steam feed pipe 36 (Fig. 3) extend along both sides of the kiln below the slot openings 15 and between the side walls and the baffles 30 or 31. These steam pipes are for the purpose of heating the kiln air. Perforated steam pipes or spray pipes 37 are similarly positioned and serve the purpose of providing necessary moisture for the kiln air. As is well known it is necessary to have some humidity in the kiln air in order to prevent the lumber from drying out too rapidly. The heating pipes as well as the spray pipes are all supported on suitable hangers.

Should the air in the kiln become too humid or should the temperature of the kiln air become higher than that desired, the temperature and humidity control will cause the ceiling ventilators 28 to open. This opening of the ventilators 28 will allow some of the air from the kiln along the central top portion of the kiln to exhaust through the ventilators. The exhausted air will ultimately be replaced by fresh air drawn in through the air inlets 26 in the suction ducts on one side of the kiln.

The manner in which my improved kiln operates will be understood from the preceding description. The drying currents of air, entering the kiln through the slot openings along one side of the kiln ceiling pass downwardly and then laterally or crossways through the lumber stacks and then out through the slot openings in the ceiling on the other side of the kiln, and from time to time the direction of the air currents is reversed. If the air becomes too hot or too humid some of the air will be exhausted through the central ceiling ventilators 28, as described, but this will occur without disturbing the drying process, and the exhausted air will be replaced by the outside air drawn into the ducts on one side. The outside air is mixed with the other air from the kiln before being drawn into the kiln, and the outside air passes the heating pipes as it goes into the kiln. Thus there is no possibility of any chilling currents of air reaching the lumber nor is there any possibility of any interference with the continual lumber drying process during the operation of the kiln. Since the outside air, during the lumber drying operation, enters only through the inlets in the ducts from which the air is being drawn into the end air chambers, the pressure of air in the kiln remains approximately the same as the atmospheric pressure outside. As a result there is no possibility of too much outside air being drawn into the kiln at any time. Thus the amount of outside air drawn into the system during the operation of the kiln is automatically limited approximately to the amount of air which is lost or exhausted from the kiln, and the amount of air lost or exhausted from the kiln is controlled by the automatic operation of the ventilators 28 which in turn are operated by a well known temperature and humidity regulating control device.

The arrangement of the ducts 16, 17, 18 and 19 reduces the number of fans required for circulating the air through the kiln and insures that all the air circulating through the system will pass through the lumber. As a result the volume

of circulating air is efficiently utilized and a corresponding amount of lumber drying can be performed in my improved kiln with a smaller supply of air than is the case with some of the other lumber drying kilns now in use.

A simple set of switches enables the entire lumber drying operation of the kiln to be controlled very easily and simply by a single operator from a control room 25 at one end of the kiln only, and finally adjustments to suit various conditions for different types of lumber or for lumber in various stages of drying, can very easily be made merely by adjusting the temperature and humidity accordingly as desired. Conditions within the kiln for any one time during the continuous operation are always uniform.

I claim:

1. In a dry kiln of the character described, a ceiling wall, a row of transversely extending slot openings in said ceiling wall along each side thereof, pairs of ducts located above and on opposite sides of said ceiling and extending over said slot openings, each duct extending along the kiln from one end of the kiln, each duct having a roof sloping downwardly from the end of the duct adjacent an end of the kiln to the opposite end of the duct, an air chamber located above each end of said kiln and having a pair of ports connecting respectively with the pair of ducts at that end of the kiln, a fan in each port, means for rotating said fans, means for controlling and reversing the rotation of said fans, the fans in the ports of each of said chambers so arranged and rotated that air will be drawn from one duct into the chamber and driven from the chamber into the other opposite duct, outside air inlets in the roofs of said ducts, means for opening and closing said inlets, a plurality of ventilators located along the center line of the kiln ceiling between opposite ducts, and means for opening and closing said ventilators.

2. In a dry kiln having a ceiling wall, a row of equally spaced, transversely-extending slot openings of identical size in said ceiling wall along each side thereof, pairs of ducts of similar size and shape located above and on opposite sides of said ceiling and extending over said slot openings, each duct extending along the kiln from one end of the kiln, each duct having a roof sloping downwardly from the end of the duct adjacent an end of the kiln to the opposite end of the duct, an air chamber located above each end of said kiln and having a pair of ports connecting respectively with the pair of ducts at that end of the kiln, the cross sectional area of each port being approximately equal to the total area of the slot openings covered by the respective duct, a fan in each port, means for rotating said fans, means for controlling and reversing the rotation of said fans, the fans in the ports of each of said chambers so arranged and rotated that air will be drawn from one duct into the chamber and driven from the chamber into the other opposite duct, outside air inlets in the roofs of said ducts, means for opening and closing said inlets, a plurality of ventilators located along the center line of the kiln ceiling between opposite ducts, and means for opening and closing said ventilators.

3. In a dry kiln having a ceiling wall, a row of slot openings of identical size in said ceiling wall along each side thereof, pairs of ducts of identical size and shape located above and on opposite sides of said ceiling and extending over said slot openings, each duct extending along the kiln from one end of the kiln to approximately the longitudinal middle of the kiln, each duct having a roof sloping downwardly from one end of the duct to the other, an air chamber located above each end of said kiln and having a pair of ports connecting respectively with the pair of ducts at that end of the kiln, a fan in each port, means for rotating said fans, means for controlling and reversing the rotation of said fans, the fans in the ports of each of said chambers so arranged and rotated that air will be drawn from one duct into the chamber and driven from the chamber into the other opposite duct, outside air inlets in the roofs of said ducts, means for opening and closing said inlets, said latter mentioned means operating to open the inlets of the ducts from which air is drawn into said chambers while closing the inlets of the opposite ducts, a plurality of equally-spaced ventilators located along the center line of the kiln ceiling between opposite ducts, and means for opening and closing said ventilators in unison.

4. A dry kiln of the character described including a ceiling wall, a row of transversely-extending slot openings in said ceiling wall along each side thereof, pairs of ducts of similar size and shape located above and on opposite sides of said ceiling and extending over said slot openings, each duct extending along the kiln from one end of the kiln, each duct having a roof sloping downwardly from the end of the duct adjacent an end of the kiln to the opposite end of the duct, an air chamber located above each end of said kiln and having a pair of ports connecting respectively with the pair of ducts at that end of the kiln, a fan in each port means for rotating said fans, means for controlling and reversing the rotation of said fans, the fans in the ports of each of said chambers so arranged and rotated that air will be drawn from one duct into the chamber and driven from the chamber into the other opposite duct, outside air inlets in the roofs of said ducts, means for opening and closing said inlets, a plurality of ventilators located along the center line of the kiln ceiling between opposite ducts, means for opening and closing said ventilators, baffles extending a short distance downward in the kiln from the ceiling, parallel to the sides of the kiln and positioned beyond the inner ends of said slot openings, whereby to prevent the short-circuiting of air current in the top of the kiln, and means for heating the air currents.
